A. F. BRIDGE

GAS HOLDER

Filed Dec. 7, 1921

Fig. 1.

Inventor:
Arthur F. Bridge,
By *James T. Brinkley*
his Attorney.

UNITED STATES PATENT OFFICE.

ARTHUR F. BRIDGE, OF LOS ANGELES, CALIFORNIA, ASSIGNOR OF ONE-FOURTH TO MORETON R. THOMPSON AND ONE-FOURTH TO FRANKLIN S. WADE, BOTH OF LOS ANGELES, CALIFORNIA.

GAS HOLDER.

Application filed December 7, 1921. Serial No. 520,534.

To all whom it may concern:

Be it known that I, ARTHUR F. BRIDGE, a citizen of the United States, residing at Los Angeles, in the county of Los Angeles, 5 State of California, have invented certain new and useful Improvements in Gas Holders, of which the following is a specification.

This invention relates to gas holders of the general type referred to in my U. S. 10 Patent No. 1,426,145, dated Aug. 15th, 1922, gas holders. In said patent I explain a type of holder wherein the gas, upon being pumped or fed into the gas chamber, displaces water therefrom into an upper chamber 15 through a connecting pipe that opens into the lower chamber near its bottom. In such an arrangement the two chambers are of substantially equal size, the upper chamber being large enough to hold all of the 20 water which, when the gas holder is empty, completely fills the lower chamber. Consequently, in such an arrangement, the water chamber must be of equal capacity with the gas chamber.

25 The present invention has to do with improvements in the gas holder shown in said Patent 1,426,145; and the main object of this present invention, together with that explained in another co-pending application, filed on even date herewith, Serial No. 30 520,533, entitled "Gas holders," is to reduce the total size of the gas holder, in proportion to its gas capacity. In accordance with the present invention I provide, instead of 35 a single gas chamber, a plurality of gas chambers, and provide but a single water chamber to serve all of the gas chambers; so that, by making a gas holder with say three gas chambers and one water chamber 40 it is only necessary to have a water chamber that is approximately one-quarter the size of the complete holder. Of course, by increasing the number of the gas chambers further, even this proportion may be reduced. Theoretically, there is no limit to 45 the number of chambers into which any given holder may be subdivided, and therefore, no theoretic limit to the number of gas chambers that may be served by one 50 water chamber; but of course in practice there is a most economical number of gas

chambers which may be served from one water chamber. If the number of gas chambers is increased too much, the increased cost of construction becomes greater than the 55 saving.

The above described broad feature of this invention is common subject matter between this application and said co-pending application filed on even date herewith, Serial 60 No. 520,533; that broad feature being in the use of a plurality of gas chambers served by a single water chamber. The distinction between these two applications is this: That whereas in said co-pending application the 65 gas is stored in the various chambers under different pressures, in the device of this present application the gas is stored in the various chambers under equal pressures and the claims in this present application will be (so 70 far as the situation between the various applications is concerned) limited to the multiple gas chamber structure in which the gas is stored at equal pressures; while said co-pending application carries, besides the 75 claims specifically to structure for storage of gas at different pressures, also the broader claims to the broad feature of a plurality of gas chambers served by a single water chamber.

80

The invention will now be best understood from the following detailed description of a preferred and specific form of apparatus that embodies the invention, reference for this purpose being had to the accompanying drawings in which—

Fig. 1 is a diagrammatic view in vertical section illustrating the holder and its charging and discharging system; and Fig. 2 is an enlarged longitudinal section showing the 90 valve operating mechanism.

It will be understood of course that in the accompanying drawings, as in this specification, I explain only the simple elements of the holder, and its accompanying apparatus; it being unnecessary to enter into details as to construction of the walls and partitions of the holder, and their bracing or staying against pressure, and unnecessary to enter into details of constructions of 100 such things as valves and regulators, as all such are well known.

In the drawings I illustrated diagrammatically a tank construction, which may typically be a steel tank that is divided into three gas chambers 10, 11 and 12, and a water chamber 13, by partitions 14, 15 and 16. Chambers 10, 11 and 12 are preferably of equal size, while chamber 13 is somewhat larger than the gas chambers, in order to hold the excess quantity of water which is necessary as hereinafter explained. The inlet pipe for the system leads in at 20 through a pressure regulator R^1 and a check valve 21, communicating with a pipe 22. Outlet pipe 23 also communicates through its regulator R^2 and check valve 24, with the pipe 22. Pipe 22 and pipes 25, 26, and 27, which connect with pipe 22 and connect into the tops of the gas chambers 10, 11 and 12, respectively, form the piping system for introducing and withdrawing gas to and from the chambers. Each chamber has a water communication from a point near its bottom to a point near the bottom of the chamber immediately above; and this water communication is formed by a stand pipe 30 with branches 31, 32, 33 and 34 leading to the bottoms of the four chambers. In the water communication thus formed between the chambers 10 and 11 there is a valve 35; and in the water communication thus formed between the chambers 11 and 12 there is a valve 36. On the gas pipe 25 there is a valve 37, and on the gas pipe 26 there are two valves at 38 and 39; while on the gas pipe 27 there is a valve 40. In addition to the gas and water piping systems, there are two air pipes 41 and 42 that lead from the tops of chambers 11 and 12, respectively; and these pipes are controlled by valves 43 and 44, respectively. Valves 35, 37, 38 and 43 are all operated by a common valve stem 45 which is moved by a piston 46 that is subjected, by means of communicating pipe 47, to the water pressure in the stand pipe 30 near its bottom. Likewise, the valves 36, 39, 40 and 44 are all operated by a common valve stem 48, that is operated by a piston 49 subjected, through pipe 50, to the water pressure in the standpipe 30 at a point near the bottom of chamber 11. The arrangement is such that when a sufficient pressure is exerted on piston 46, then valves 35, 37, and 43 are closed, and valve 38 is open; while when the pressure is relieved, valves 35, 37 and 43 are opened, and valve 38 is closed. Similarly, when sufficient pressure is exerted on piston 49, then valves 36, 39 and 44 are closed, and valve 40 is open; while when the pressure is relieved, valves 36, 39 and 44 are open and valve 40 is closed. Many different mechanical arrangements may be made for effecting these operations; I simply show a typical mechanical arrangement. For instance, the movement of the piston toward the right may be opposed by a suitable spring 51 (see the

detail in Fig. 2); and a screw-threadedly adjustable follower 52 may be used to regulate the pressure of the spring 51; so as to regulate the pressure at which the various valves will open and close.

The holder is first charged with the required amount of water; enough to fill the lower chamber 10 and to fill the next chamber 11 up to about the level indicated at L^1 . When gas is sent in under suitable pressure through the pipes 20 and 22, it passes through pipe 25 into the upper part of chamber 10, displacing the water in that chamber, and the water passes up through pipe 30 and through branch pipe 33 into chamber 11, until that chamber is filled, and then the water passes on up through pipe 30 and through branch pipe 32 into chamber 12; so that when chamber 10 is full of gas then the water level stands about as indicated at L^1 in chamber 12. It is at the pressure of this head of water that the full charge of gas in chamber 10 is stored. As soon as the water level reaches this point, the pressure on piston 46 is sufficient to move that piston toward the right and to close valves 35, 37 and 43, and to open valve 38. Valve 43 has been open up to this time, and has allowed the air in chamber 11 to escape. The pipe 41 may have an inverted trap 41^a that will prevent the escape of water.

As soon as the valves have moved to their last described positions, then the inflowing gas will flow through pipe 26 and through the open valve 38 and through valve 39, which at that time is also open, and into the upper part of chamber 11, displacing the water in that chamber and forcing it up through stand pipe 30 into the next chamber 12; and as soon as that chamber is full of water, then through the standpipe 30 and branch 31 into the water chamber 13. When chamber 11 is full of gas, then the water level stands at L^2 in chamber 13; and then the pressure on the piston 49 is sufficient to close the valves 36, 39 and 44 and to open the valve 40. The valve 44 is the air escape valve on air pipe 42, and has allowed the air in chamber 12 to escape. This pipe may also have an inverted trap 42^a to prevent escape of water.

Then the gas passes up through pipe 27 and through open valve 40 into the upper part of chamber 12, displacing the water in that chamber and forcing it up through pipe 30 and branch pipe 31 into the water chamber 13, until the chamber 12 is filled with gas. When chamber 12 is filled with gas then the water level stands at approximately the point shown at L^3 , near the top of chamber 13. The holder is now filled to capacity; and it will be noted that each one of the gas chambers has been filled with gas under the same pressure as the others, and when filled has been closed off from the

others by the action of the valves. When the holder is full, there is no gas communication between the several gas chambers, and further there is no water communication to 5 any of the gas chambers except the uppermost; these communications having been shut off by the closure of the several valves.

When gas is withdrawn from the holder the reverse operation takes place. When the 10 holder is full, the only gas line that is open is the pipe line 27, in which the valve 40 is open. Consequently, when the gas is withdrawn through outlet pipe 23, gas will first be withdrawn from the chamber 12, allowing 15 the water from chamber 13 to flow into chamber 12 to displace the gas therein. The minimum pressure under which the gas is withdrawn, and the pressure that the regulator R^2 is set to draw off, is that pressure 20 that is caused by the head of water standing at level L^2 in water chamber 15 when chamber 12 is full, or substantially full, of water and the last of the gas is being withdrawn from that chamber. When the water level 25 reaches L^2 again, then the pressure on piston 49 is relieved, and the valves connected to that piston move to the positions shown in Fig. 1. This closes the valve 40 and opens the valves 36, 39 and 44; and then gas begins 30 to flow out of chamber 11 into the delivery pipe, allowing the water to come down into chamber 11 and allowing the water level to fall in chamber 12. At this time the valve 44 is open, allowing air to enter chamber 12 35 to relieve the vacuum that would otherwise be formed there. As soon as the gas chamber 11 is exhausted of gas and the water level has fallen again to L^1 , then the pressure on piston 46 is relieved, and the lower piston 40 moves to its position shown in Fig. 1, closing valve 38 and opening valves 35, 37 and 43. Valve 43 being open, allows air to enter 40 chamber 11 as the water level falls in that chamber, and valve 37 allows the gas to be 45 withdrawn from chamber 10. As the gas is withdrawn from that chamber, the water passes down through standpipe 30 and branch pipe 34 into the chamber 10, rising in that chamber as gas is displaced; and 50 when all the gas has been withdrawn, the water level stands again at L^1 .

It will of course be understood that this description is merely typical of devices that may be made in accordance with my invention. The various details may be varied. I have explained specific details not to limit the invention but to clearly and fully describe one form of it. The number of gas chambers may be varied; the only limit in 55 this form of holder is the structural limit to the height of the tank. Of course the several chambers need not be built in the same structure; it is only necessary that they be arranged at levels that will cause the water 60 to flow between them and the water cham-

ber. Consequently I do not wish the invention to be limited except as may be expressly stated in the following claims.

An advantage of this specific type of holder is that the lower chamber or chambers 70 only have to be constructed heavily enough to hold the pressure due to the static water head as described: for instance, as for chamber 10, the head when the water level is at L^1 . If anything should occur in the valve 75 system to allow the water from uppermost chamber 13 access to chamber 10 for instance, an excessive pressure would be put on it. The putting of a dangerous pressure on that chamber can be relieved by any suitable 80 safety relief, as for instance a water trap pipe 60 in which a body of water will normally stand and having its upper end somewhat above the level L^1 , so that any pressure greater than that represented by level 85 L^1 will force out the water and give relief to chamber 10. Of course the same arrangement may be applied to chamber 11. The gas chamber 12 needs no such provision and the upper chamber 13 may have a roof 90 with an air vent 58.

Having described a preferred form of my invention, I claim:

1. A gas holder of the water displacement type, characterized by a plurality of separate gas chambers and a water chamber, gas communication to each gas chamber, water communication between the several gas chambers and the water chamber, and means to close the water communication to a chamber when it is filled with gas. 95

2. A gas holder of the water displacement type, characterized by a plurality of separate gas chambers and a water chamber, gas communication to each gas chamber, water 105 communication between the several gas chambers and the water chamber, and means to close the water and gas communication to a chamber when it is filled with gas.

3. A gas holder of the water displacement 110 type, characterized by a plurality of gas chambers and a water chamber, gas communication to each gas chamber, water communication between the several gas chambers and the water chamber, and means to 115 close the water communication to a chamber when it is filled with gas; the gas chambers being arranged at successively higher levels and the water chamber above all the gas chambers. 120

4. The gas holder of claim 1, further characterized by valves actuated by the water pressure in the chambers to close the water communication to a chamber.

5. The gas holder of claim 1, further characterized by valves actuated by the water pressure in the chambers to close the water and gas communication to a chamber. 125

6. A gas holder of the water displacement type, characterized by a plurality of 130

- gas chambers arranged at successively higher levels and a water chamber above the highest gas chamber, a gas inlet and discharge pipe leading into the top of each gas chamber, an air pipe leading to the top of all the gas chambers except the lowermost chamber, a water intercommunication pipe the gas chambers except the lowermost chamber, a water intercommunication pipe leading into the bottom of each of the chambers, valves on each of said pipes, and pressure operated means subjected to the water pressure in the water communication pipe to open and close said valves.
- 15 7. A gas holder of the water displacement type, characterized by a plurality of sep-

arate gas chambers arranged one above another and a water chamber above the highest gas chamber, water communication between the bottom of each chamber and the bottom of the chamber next above it, gas communication to each gas chamber for the introduction of gas to displace water into a chamber above, and valvular means actuated by virtue of the changing water level to control the water and gas communications.

In witness that I claim the foregoing I have hereunto subscribed my name this 30th day of November, 1921.

ARTHUR F. BRIDGE.
